UNITED STATES PATENT OFFICE.

HENRY ARTHUR THOMPSON, OF WITHTINGTON, MANCHESTER, ENGLAND.

ACTUATING SIGNALS ON AND COMMUNICATING WITH TRAINS.

1,227,021.

Specification of Letters Patent.

Patented May 22, 1917.

Application filed June 22, 1915. Serial No. 35,530.

To all whom it may concern:

Be it known that I, HENRY ARTHUR THOMPSON, a subject of the King of Great Britain and Ireland, residing at 25 Derby road, Withington, Manchester, in the county of Lancaster, England, have invented new and useful Improvements for Actuating Signals on and Communicating with Trains, of which the following is a specification.

10 My invention relates to railway inductive signaling or control and consists in the provision of electrical apparatus capable of responding directly and indirectly to the pulsations of a track magnetic field. While this 15 invention does not include any arrangement of track circuits it may be assumed that the inductive connection between the track and the vehicle collapses or is rendered inoperative upon a signal being put to danger.

20 I propose to modify for the purpose of detecting the feeble currents induced in the train circuit the construction of a type of relay much used in telegraphy, such relay sending electrical impulses through the coils 25 of and setting up vibratory motion in a reed device whose function in turn is to produce a continuous note and to act as a relay for the actuation of a solenoid or the like.

It is to be understood that my invention 30 is intended for use in conjunction with any suitable track circuit system wherein such circuits are automatically controlled by the operation of the line signals or appliances therefor.

35 In order that my invention may be understood I append hereunto three sheets of drawings.

Figure 1 is a front elevation of the pole-changing relay, without the coils, showing 40 the position of the cores and pole-pieces relative to the armatures and the position of the lower armature relative to the contact screws; also means for adjusting the armatures.

45 Fig. 2 is a plan of the upper portion of the pole-changing relay showing the position of the upper armature relative to the upper pole-pieces and the bent permanent magnet.

50 Fig. 3 is a plan of the lower portion of the pole-changing relay showing the position of the lower armature relative to the lower pole-pieces and the contact screws.

Fig. 4 is a front elevation of the pole-

changing relay showing the manner of 55 winding the cores.

Fig. 5 is a side elevation of the pole-changing relay with the cores removed showing the two armatures attached to the pivot. 60

Fig. 6 is a side elevation of the vibrator showing the component parts of the reed and its position relative to the permanent magnet.

Fig. 7 is a plan of the vibrator showing 65 the method of holding the flanking springs.

Fig. 8 is a plan of an alternative type of reed showing the twin armature and the flanking springs.

Fig. 9 is a side elevation of the reed and 70 shows the position of a flanking contact spring and holder.

Fig. 10 shows the connections of the train circuits as a whole.

The following is a description of an old 75 and well known telegraph relay as modified to suit the purpose of this invention.

The cores 1, Figs. 1 and 4, are of unusual length and with the pole pieces 2, which are extended as shown, are constructed in the 80 manner usual to alternating current apparatus. Said pole-pieces are curved as in Figs. 2 and 3 where they face the armatures in order that the tractive force may be exerted at the requisite point. 3 is a pivot of 85 non-magnetic metal over the ends of which are threaded and fixed two short armatures 4 and 5 preferably shaped as in the drawing. The lower armature owing to its extension 6 is rather longer than the other. 90 The ends of the pivot rotate in jeweled or metal bearings 7. The permanent horseshoe magnet 8 is bent as in Fig. 2 to economize space. The poles N and S of the permanent magnet are brought into close proximity to the fixed ends of the armature as in 95 Figs. 2 and 5. Alternative types of magnets may be used. 9 and 10 are two platinum tipped contact screws held in the usual way by shoulders 11 and 12. Said screws are 100 disposed on either side of the lower armature extension 6 so that the latter may play between them. The electro-magnets should be at least 3½ inches in height the measurement being taken from the bottom of the 105 lower pole-pieces to the top of the upper pole-pieces.

One of the chief characteristics of this

relay, which on account of its preferred function herein described may be termed the pole-changer, is the manner in which the cores are wound. This is shown in Fig. 4. Each core is encircled by two separate coils. A current entering at terminal t^1 finds its way to terminal t^4 by means of four paths:—(a) through the left lower coil, (b) through the right lower coil, (c) through terminal t^5 , the left upper coil and terminal t^6 , (d) through terminal t^2 , the right upper coil, and terminal t^3 .

Each coil should consist of No. 38 British standard wire gage copper wire wound to a resistance of 200 to 300 ohms. I may use enameled wire for the purpose. I do not confine myself to the use of multiple winding or to the employment of the type of wire specified.

The pivot 3 is connected to terminal 13 (Fig. 3) by means of a very fine flexible phosphor bronze or copper wire 14 it being essential that the movement of the armatures should be unhampered by such connection. The contact screws 9 and 10 should be adjusted so that the movement of the armatures is almost imperceptible to the eye and so that virtually the armatures lie equi-distant between their respective pole-pieces when out of contact with said contact screws.

The ideal distance between the curved faces of the pole pieces and the armatures may be found by experiment, attention being given to the fact that the close propinquity of the former and the latter does not necessarily mean the attainment of the most sensitive position.

As there is no necessity to give bias to the armatures as in ordinary telegraphy the need for the usual elaborate adjusting apparatus may not arise. The adjustment should be accurately and definitely fixed in the workshop. I may however use additional means of adjustment such as that illustrated in Fig. 1 wherein the supports 11 and 12 are mounted on a movable carriage 15 and insulated therefrom by a strip of insulating material 16, said carriage working on the suitably mounted adjusting screw 17 and guide 18. The coils of said relay are contained in the circuit of a coil which is wound around a vehicle and are energized by the feeble secondary currents induced therein by the pulsations of the track magnetic field. A condenser K is shunted across the terminals t^5 and t^6 of the train coil A Fig. 10. The relay as reconstructed should respond to induced currents due to an extremely low induced electro-motive force and will be much more sensitive than the standard pattern designed for general telegraphic purposes. Other types of non-resonant polarized relays operative by the feeble induced cur-

rents may with advantage be used, such as, for instance, relays belonging to the "moving coil" class, it being sufficient for the purpose of this invention that the relay employed be of the polarized description.

By the co-action of the above described pole-changing relay with a vibrator of the following type a sustained audible indication is produced in the cab of the locomotive of the presence of the induced currents in the train coil. Said indication is intended to act as a "clear" signal to the driver and is a new feature in inductive signaling of this class and such signal is the most important feature of my invention.

This "clear" signal cannot be given accidentally by a "short circuit" on the train and herein lies the distinctive merit of my invention.

To the permanent magnet 19, Figs. 6, 7, 8 and 9, is attached the yoke 20 of electromagnet 21. Screwed to the upper pole of the permanent magnet are two iron or steel blocks 22 and 23. Clamped between said blocks in the usual way and insulated therefrom is the reed R. One type of reed is composed of three sections:—a strip of nickel 24, an armature of soft iron or steel 25, and a flexible nickel extension 26 to which is attached a hammer 27. Another and perhaps better type of reed consists of a strip of nickel 28; two thin strips of soft iron or mild steel 29 and 30, forming a twin armature; and a flexible extension 31. In the latter case the two strips of iron or steel are attached to the fixed strip 28 and extension 31 in the manner roughly indicated in Fig. 8. In each type of reed the nickel will bend more readily than the armature and the latter being more or less rigid nodular vibration will be prevented. The function of the hammer is to strike against sounding attachments 32 and 33, preferably bell metal tubes, in order that a mellow note may be produced in the cab of the engine. Various types of sounding attachments may be used.

The coils of the polarized vibrator are connected to the terminals of the pole-changing relay and the battery in the manner indicated in Fig. 10. A current flows from battery terminal t^7 to battery terminal t^8 via the terminals t^9 and t^{10} of the reed device, armature pivot 3 and contact screw 9; or from terminal t^{11} , contact screw 10, and pivot 3 to terminal t^5 via terminals t^{10} and t^9 ; according to the position of the pole-changing armature.

When the line is clear and the armatures of the pole-changing relay are first actuated by the feeble alternating current induced in the train coil A by the alternating magnetic field having its source in generator G and radiating from the line wire L which is controlled by the switch X, a reversing

current from the divided battery is directed through the coils of the vibrator and the reed begins to vibrate.

Owing to the strength of the current and to the application of the tractive force near the fixed end of the reed, the latter will vibrate sufficiently to enable the hammer to strike against the stationary sounding attachments although the natural period of the reed's vibration may not exactly synchronize with the frequency of alternation of the track magnetic field. It is known that when the amplitude of the vibrations of a reed, tuned to the frequency of a current is restricted by the contact of the reed with flanking springs or stationary objects the rate of vibration is accelerated and no longer synchronizes with the periodicity of the attractive and repulsive forces exerted on the reed armature. Therefore if the natural period of the reed's vibrations be initially synchronous with the periodicity of the current the harmony will be destroyed when the reed strikes against the stationary objects. The resultant discord will cause the reed to vibrate in an uncertain and unsatisfactory manner. I propose to take advantage of the fact that in my invention the reed will respond to electrical impulses not quite in step with the natural period of the reed's vibration, to make the accelerated rate of vibration of the reed synchronous with the periodicity of the current in the track circuit. By attaching the hammer to the flexible extension further freedom of action is allowed the reed and a really satisfactory result should be obtained. For ideal results the electro-motive force of the battery should be fairly constant.

I propose to provide an alternative or additional method of signaling or control, namely, means for the actuation of a valve controlling solenoid which will perform the function common to cab signaling systems.

I propose to attach to the reed instrument a type of flanking contact spring long employed successfully in automatic telegraphy. The vibrations of such springs are damped so that in its excursions to and fro the reed will always find a spring in position for contact. The contact will be long and the break short and a virtually continuous current will be relayed to actuate the solenoid or the like for the purpose desired.

A crosspiece 34 is attached to the reed and provided with platinum contacts. When the reed is at rest this cross-piece is out of contact with the stiff hooked flanking springs 35 and 36 shown in Figs. 7 and 8. Said cross-piece should make effective contact with the flanking springs before the hammer touches the sounding attachments. The pole-pieces of the reed electro-magnet are preferably designed so that they may if desired act as clamps for the hooked flank-

ing springs. Two blocks of soft-iron 37 and 38 are pivoted and fixed on the upper ends of the cores 39 and 40. Between said blocks and soft iron blocks 41 and 42 are clamped hooked springs 35 and 36. Said hooked springs can only move appreciably in one direction *i. e.* away from the reed since projections 43 and 44 of non-magnetic metal brackets 45 and 46 engage with the hooks when the springs tend to move toward the reed. The metal brackets 45 and 46 are suitably fixed to blocks 37 and 38. The vibrations of the flanking springs are thus damped and effective contact with the reed crosspiece 34 is insured. Since the pole-pieces are pivoted to the cores and the flanking springs are fixed to the pole-pieces the position of the hooked springs may be adjusted by a slight rotary movement of the pole-pieces. The hooked springs may be composed of steel, phosphor bronze, nickel, or other suitable metal and may be fitted with platinum contact pieces. The path for the current energizing the solenoid is through the hooked springs, the pole-pieces, the cores, and the permanent magnet.

In order that a substantially continuous current may be relayed to energize the solenoid for the purpose of preventing the plunger 47 from dropping the terminals of said solenoid should be connected to the flanking springs and battery in the manner indicated in Fig. 10 so that a current may circulate from terminal t^{11} of the divided battery through terminals t^{12} and t^{13} of the solenoid, the flanking springs 35 or 36 and the reed R to battery terminal t^2 .

When an inductive connection between the track circuit and the train coil A is established the reed vibrates and the plunger 47 is sucked into the solenoid coil. Upon the collapse of the inductive connection the reed will cease to vibrate, allowing the plunger to drop. When the inductive connection is broken for only a momentary period the continuous note may be interrupted before the solenoid circuit is disconnected if the flanking springs are adjusted to produce this effect; that is, if the flanking springs are brought very close to the reed cross-piece.

In order to prolong the magnetization of the solenoid I may wind the solenoid coil on thin copper sheathing 48. To prevent sparking at the contacts I propose to shunt a high resistance 49 across the coils of the vibrator and a high resistance 50 across the terminals of the solenoid.

The resistance of the train coil should be as low as practicable. The pole-changing relay is wound to suit this low resistance and thus to obtain a larger magnetizing current than would be obtainable with series winding.

If the periodicity of the current in the ground circuit be sufficiently low I may use

130

a non-polarized vibrator. In such case the function of the sensitive relay operative by the feeble induced currents will be to send uni-directional impulses through the coils of the vibrator. Be it noted that since the non-polarized vibrator will not be provided with an interrupting device it will not be actuatable by a continuous current or the equivalent thereof.

10 I am aware that other types of polarized relay might be employed for the purpose of detecting the presence of the induced currents but the use of such relays will not evade my invention the cardinal feature of 15 which is the operation of a tuned vibrator by means of a battery current.

I declare that what I claim is:

1. In a railway inductive signaling or control system a polarized reed relay possessing 20 a tongue composed of a relatively flexible part fixed at one end and a comparatively rigid portion fixed to said flexible part, such components forming a whole which is set in vibratory motion by the action of magnetic forces of predetermined periodicity applied near the junction of said parts, a pair of flanking contact springs so disposed as to make contact with said reed when in vibration; such combination being so characterized that when the reed is set in motion its contact with the flanking springs brings the vibrations of the reed into synchronism with the periodicity of said magnetic forces, current impulses being sent through a local circuit of which the reed and flanking springs form a part.

2. In a railway inductive signaling or control system a combined polarized reed relay and acoustic device possessing a tongue composed of a relatively flexible part fixed at 35

one end, a comparatively rigid part fixed to said flexible part, and a short hammer-carrying flexible extension attached to said rigid portion, such components forming a whole which is set in vibratory motion by the action of magnetic forces of predetermined periodicity applied near the junction of said parts, a pair of flanking contact springs and a sounding attachment so disposed as to be capable of making contact with said reed; such combination being so characterized that when the reed is set in motion its contact with the flanking springs and sounding attachment brings the vibrations of the reed into synchronism with the periodicity of said magnetic forces, current impulses being sent through a local circuit of which said reed and flanking springs form a part and an audible signal being given by the contact of the hammer with said sounding attachment.

3. In a railway inductive signaling or control system a polarized reed relay possessing a vibratory armature, two hooked flanking contact springs making electrical connection with said armature when in vibration, stationary elements capable of engaging the hooked extensions of said springs and thereby preventing their inward deflection; such combination being so characterized that a local circuit controlled by said armature and flanking springs receives long current impulses at regular intervals.

In testimony whereof I have signed my name to this specification in the presence of 75 two subscribing witnesses.

HENRY ARTHUR THOMPSON.
